UNITED STATES PATENT OFFICE

KENNETH WILSON CARTER, OF SAN ANTONIO, TEXAS.

HIGHWAY FOR GRADE-CROSSINGS.

1,391,995.

Specification of Letters Patent. Patented Sept. 27, 1921.

Application filed October 29, 1920. Serial No. 420,416.

To all whom it may concern:

Be it known that I, KENNETH WILSON CARTER, a citizen of the United States, and a resident of San Antonio, in the county of 5 Bexar and State of Texas, have invented certain new and useful Improvements in Highways for Grade-Crossings, of which the following is a specification.

My invention relates to highways for 10 grade crossings and it contemplates certain new and useful improvements in my pending application filed March 15, 1920, Serial No. 365,950.

The purpose of my present invention is 15 the provision of a highway for grade crossings which compels the drivers of vehicles to display the necessary caution when approaching a grade crossing, and permits the clear get-away of the vehicles only after 20 they have actually crossed the railway track. Furthermore, my invention provides a highway of extremely simplified construction without sacrificing efficiency.

I will describe two forms of highways 25 embodying my invention and will then point out the novel features thereof in claims.

In the accompanying drawings:

Figure 1 is a view showing in perspective one form of highway embodying my in- 30 vention.

Fig. 2 is a transverse section of the highway shown in Fig. 1.

Fig. 3 is a plan view of one half of a modified form of highway embodying my in- 35 vention.

Similar reference characters refer to similar parts in each of the several views.

Referring specifically to the drawings and particularly to Fig. 1, H designates generally a highway forming the subject matter 40 of my invention which as shown is formed as a continuation of the ordinary highway H'. The highway H', as well as the highway H, are intersected by a railway track T 45 which is disposed in the same plane as the highways so as to form the usual grade crossing.

The highway H comprises, in the present instance, two pairs of curbings C and C' 50 formed of concrete or any other suitable material, and having their upper edges rounded as shown in Fig. 2. As shown in Fig. 1, the curbings C are offset with relation to the curbings C', with the curbings of 55 each pair spaced apart in parallelism and curved longitudinally to provide a tortuous

passage or roadway designated at R and R', respectively. As illustrated to advantage in Fig. 2, the curbings of each pair project above the surface of the highway so as to 60 positively define the roadways R and R', which latter are sufficiently wide to permit of the passage of a vehicle therethrough without actually contacting with the curbings, provided that the vehicle is traveling 65 at a safe speed, as will be more fully described hereinafter.

In order to prevent a vehicle straddling any of the curbings so as to eliminate the necessity of following the roadways defined 70 by the curbings, the opposite ends of each curbing are provided with wings or lateral extensions W and W', the wings W extending from the inner curbing to the side of the highway, while the curbings W' extend 75 from the corresponding curbing to the center of the highway.

In the operation of the highway, a vehicle arriving at the entrance end of, for instance, say the roadway R, is compelled, in order 80 to pass through the highway, to traverse the roadway R. As this roadway defines a tortuous passage, it is obvious that the driver of the vehicle is forced to reduce the speed of the vehicle to such a degree that he 85 can readily stop in case of an emergency. Should he attempt to traverse the roadway at a speed above a safe speed, the wheels of the vehicle will be thrown into contact with the curbings, and by virtue of this frictional 90 engagement or braking action upon the wheels will be effected thereby reducing the speed of the vehicle to the prescribed limit. After the vehicle has traversed the roadway 95 R and the railway track T, it is obvious that as no other obstructions are provided, the vehicle can make a clear get-away.

Referring now to Fig. 3, I have here shown one half of a modified form of highway embodying my invention in which the 100 curbings are so shaped as to define a roadway with angularly and relatively abrupt bends which serve to increase the difficulty with which a vehicle can traverse a roadway at a speed above the prescribed limit. It 105 will be understood that should the vehicle attempt to traverse a roadway at an unsafe speed, the wheels of the vehicle will likewise be thrown into contact with the curbings so as to effect a braking action upon the vehicle.

Although I have herein shown and de-

scribed only two forms of highway embodying my invention, it is to be understood that various changes and modifications may be made herein without departing from the spirit of the invention and the spirit and scope of the appended claims.

What I claim is:

1. A highway for grade crossings, comprising curbings arranged in pairs at the 10 opposite sides of a railway track, with the curbings of each pair spaced apart to provide tortuous roadways, the curbings of one pair being offset with relation to the curbings of the other pair to allow of the quick 15 get-away of a vehicle after it has traversed one roadway.

2. A highway for grade crossings, comprising curbings arranged in pairs at the 20 opposite sides of a railway track, with the curbings of each pair spaced apart to provide tortuous roadways, the curbings of one pair being offset with relation to the cur-

ings of the other pair, and wings formed on the opposite ends of each curbing in a manner to prevent a vehicle from straddling 25 the curbings.

3. In combination, a railway and a highway for crossing the same, and members rising above the surface of the highway at offset points in the highway and at opposite 30 sides of the railway for causing vehicles to take a tortuous course only before crossing the railway.

4. A highway for grade crossings, comprising curbings arranged in pairs at the 35 opposite sides of a railway track, with the curbings of each pair spaced apart to provide tortuous roadways, the curbings of one pair being offset with relation to the curbings of the other pair, and means for preventing vehicles from straddling the curbings. 40

KENNETH WILSON CARTER.
